PARKING CLOCK

Application filed November 8, 1926. Serial No. 146,968.

This invention relates to an indicator adapted to show the time which has elapsed since a machine has ceased operation, for example, since a conveyance has come to rest. 5 For convenience, it is referred to as a parking clock since one of its most useful applications is as an indicator of the time during which a vehicle has been parked.

The principal object of the invention is the 10 provision of elapsed time indicating means adapted to be mounted upon a device capable of movement or operation and actuated by potential power means to indicate the time during which the device is not in motion or 15 in operation. According to the invention, the elapsed time indicating means is actuated by power means whereof the potential is adapted to be restored during the operation of the device, means being provided to return the elapsed time indicating means and 20 to restore the potential in the power means dependent upon the movement of the machine which means are retained in operative position during the movement of the said 25 device.

It is also an object of the invention to provide electro-magnetic devices for restoring the potential in the power means and returning the elapsed time indicating means to 30 initial position, dependent upon a source of electrical energy which is disconnected during the operating movement of the device although the said means are mechanically retained in operative position.

These and other objects of the invention, and the means for their attainment will be more apparent from the following detailed description taken in connection with the accompanying drawings illustrating a preferred embodiment of the invention in which:

Figure 1 is a view in front elevation showing the face of the indicator or parking clock upon which is recorded the parking time of the conveyance and, if desired, standard time.

Figure 2 is a view in side elevation showing the case in which the indicator is housed.

Figure 3 is a view similar to Figure 2 but with the near half of the case removed to show the indicator mechanism.

Figure 4 is a transverse vertical sectional view taken in the plane indicated in line 4-4 in Figure 3, looking in the direction of the arrows, and showing the power spring and the several trains of gearing actuated thereby by which the different time indicating pointers are propelled.

Figure 5 is a transverse vertical sectional view taken in the plane indicated by line 5-5 in Figure 3, looking in the direction of the arrows, and showing particularly the escape- 60 ment mechanism and cams mounted upon the power spring arbor which serve as mechanical means to retain the motion responsive devices in operative position when a spring is wound up and the elapsed time indicator returned to initial position, and which performs a second function of effecting the rewinding of the power spring after it has become un- 65 wound to a predetermined degree.

Figure 6 is a view in longitudinal vertical section taken in the plane indicated by the line 6-6 of Figure 1, looking in the direction of the arrows, and showing details of the electro-magnetic means for restoring the potential of the power means and returning the elapsed time indicator to initial position.

Figure 7 is a detail view taken in the trans- 70 verse vertical plane indicated by the line 7-7 in Figure 6 looking in the direction of the ar- 80 rows and showing the inactive position of controlling devices which are responsive to movement of the device upon which the indicator is installed at a time when the de- 85 vice is not in operation.

Figure 8 is a view similar to Figure 7 but showing the controlling devices in operative position as when the device is in operation.

Figure 9 is a view, in transverse vertical section, taken in the plane indicated by the line 9-9 in Figure 4, looking in the direction of the arrows, and showing details of the means whereby the motor energizing electric current is temporarily interrupted to permit the electro-magnetic devices to return to initial position during their operation in returning the elapsed time indicating pointers to initial position and corresponding to the relation of parts illustrated in Figure 7.

Figure 10 is a fragmentary transverse ver-

tical view similar to Figure 8 but showing the contact actuating means in the position assumed corresponding to the relation to parts illustrated in Figure 8.

- 5 Figure 11 is a view, in transverse vertical section, taken in the plane indicated by line 11—11 in Figure 6, looking in the direction of the arrows, and showing details of a ball clutch which affords a driving connection in
 10 10 one direction of rotation between the electro-magnetic means and the power means of the indicator.

- 15 Figure 12 is a view, in transverse vertical section, taken in the plane indicated by the line 12—12 of Figure 6, looking in the direction of the arrows, and showing the clutch which disengages the escapement and standard time mechanism when the potential power means and elapsed time indicators are
 20 being restored.

Figure 13 is a view showing a wiring diagram illustrating the operation of the device.

- 25 In general the invention involves a dial 14 indicating divisions of time in the illustrated embodiment, six in number, over which one or more pointers or hands 15 and 16 are propelled to indicate elapsed time, that is time which elapses between two events, such as the stopping and starting again of a conveyance, machine or device of any character capable of movement or operation. The hands are propelled by what may be broadly termed clock mechanism since the measurement of time during which the machine is at rest is
 30 35 made in units of standard time. Also combined in the indicator is standard time indicating means, hereafter referred to as a time piece, such as is illustrated by the dial 17 and the hour and minute hands, 18 and 19, respectively. In the illustrated embodiment, the potential or power means for actuating the clock mechanism takes the form of a main spring 20.

- 40 The time piece 17—19 functions constantly to give the time of day, but the elapsed time indicating means 14—16 functions only when the machine or other device upon which the indicator is mounted is not in operation or in motion. So soon as the machine stops, 45 suitable devices hereinafter to be described are caused to release the elapsed time indicating pointers 15, 16 which are then caused, by the main spring 20, to travel over the elapsed time indicating dial 14 and their 50 travel is continued until the machine starts, when the progress of the hands 15, 16 is arrested and they are returned to initial position, indicated by the ordinal zero, in Figure 1, by a movement which simultaneously 55 60 restores the potential in power spring 20. In the illustrated embodiment the elapsed time indicating dial is shown as divided into only six subdivisions to represent six hours of inactivity of the device upon which the indicator is mounted. Obviously, any number
 65

of hours may be indicated and the mechanism adjusted to operate for such period, but only six hours parking time is provided for in the illustrated embodiment as all that is required from practical considerations, as 70 municipalities which find it necessary to restrict the parking of vehicles do so for periods of less than the six hours, or not at all. The instrumentalities availed of to effect this movement are shown as electro-magnetic devices which are energized by any convenient source of electrical energy indicated conventionally at 22 in Figure 13. This energization is controlled by devices responsive to movement of the device when in operation, specifically the swaying of a conveyance. 75

80 Referring particularly to Figure 4, the indicator mechanism includes what may be termed a center shaft 24 which is rotated in one direction, to wit, a clockwise direction by the main spring 20 and in turn is operably connected by trains of gears, to be described, to the respective indicating hands 85 15, 16 and 18, 19 of the parking and time 90 clocks 14 and 17 respectively. The center shaft is rotated in the opposite direction by the electro-magnetic devices to wind the main spring and return the parking hands to initial position. A ball clutch 26 between the center shaft 24 and the standard time indicating mechanism 17—19 and escapement mechanism 27 permits the center shaft 24 to drive the parking clock hands 15, 16 and the standard time indicating hands 18, 19 in clockwise direction and operates the escapement 27 but uncouples the time clock and escapement when rotated in the opposite direction, i. e. in a counter-clockwise direction, by the electro-magnetic devices. The main spring 20 is mounted on an arbor 28 journaled at its ends in the front and rear clock frame members 30 and 31 and is secured at one end to a pin 33 Figures 4 and 5 and at 100 its other end to the arbor 28 to rotate the arbor. It is positioned between a disc 35 freely 105 rotatable upon the arbor 28 and carrying a flange 36 serving to space the disc from the rear frame 31 and a gear 37 fixed on the arbor 28 by which the center shaft 24 is rotated through the pinion 38 with which the gear 110 meshes. The gear 37 and pinion 38 form mechanical means to drive the shaft section 24 from the arbor or another shaft section 28. The gear 37 and pinion 38 may also be called 115 a driving connection between the arbor 28 and the shaft 24. 120

125 The pinion 38 is carried on the plate 39 fastened upon an inner member 26 of a ball clutch indicated as a whole at 40 so that clockwise rotation of the pinion 38 by the gear 37 turning in a counter-clockwise direction by the unwinding of the spring 20 causes engagement through balls 41 of an outer clutch member 42 freely rotatable on a hub carried by the inner member 26 of the 130

ball clutch. On the extreme front end of the center shaft 24, the elapsed time minute hand 15 is carried and by which the said hand is propelled over the dial 14.

5 The outer clutch member 42 has formed thereon a gear 45 concentric with the shaft 24. The gear 45 meshes with a pinion 48 carried by an arbor 49 journaled in the front and rear frames 30 and 31, which pinion is 10 the first member of a train of gears connecting the gear 45 with the escapement 27. The arbor 49 carries rigidly therewith a gear 50 meshing with a pinion 51 rigidly mounted on the arbor 52 with the gear 53 which in turn 15 meshes with a pinion 54 mounted upon an arbor 55 carrying the toothed wheel 56 forming one of the elements of the escapement 27. The escapement may take any form, that 20 illustrated being a common form of escapement used in clocks and which in usual fashion controls the rotation of the center shaft 24 and hence the unwinding of the spring 20 in synchronism with standard periods of time.

25 The pinion 46 on the inner clutch member 26 drives the elapsed time hour hand 16 at a speed proportionately slower than the minute hand as will be understood. This hour hand 16 is carried upon a sleeve or hollow shaft 60 concentric with the end of shaft 24 and is rotated by the pinion 46 meshing with a gear 61 fixed upon one end of an axle journaled in the front frame 30 and carrying upon its front end in front of the 30 front frame 30 a pinion 62 which meshes with a gear 63 carried on the hollow shaft 60. By suitably proportioning the pinions 46, 62 and gears 61 and 63 the hour hand 16 may be propelled over the face of dial 14 at a rate to 35 indicate hours of parking time while the minute hand 15 is directly propelled by the shaft 24 and hence by the mainspring 20 whereof the rate of unwinding is controlled by the escapement at a rate to indicate hours 40 of parking time.

The standard time indicating hands, to wit, the minute hand 18 and the hour hand 19 are mounted upon what may be called a clock shaft 65 also journaled in the front and rear frame members 30 and 31, the minute hand 18 being directly carried on the end of the shaft and the hour hand 19 being carried upon a sleeve or hollow shaft 66 concentric with the clock shaft 65.

55 The clock shaft 65 is rotated by the main spring 20 by a train of gears now to be described. An idler gear 68 pivotally mounted on the front frame member 30 meshes with and is rotated by the gear 45 carried with the outer ball clutch member 42 and in turn meshes with a gear 69 loose on the shaft 65 but capable of frictionally driving the same by a spring clutch connection therewith consisting of a coil spring 70 disposed between 60 an abutment 71 fastened on the shaft 65 and

a collar 72 which is loosely mounted on the clock shaft 65 and which tends to press the collar against a flange 73 formed on or carried with the gear 69. In the illustrated embodiment this flange is shown as a pinion since stock clock parts may be conveniently used in the assembly of the indicator. Thus rotation of the center shaft 24 under the action of spring 20 causes the rotation of the gear 69 and with it the clock shaft 65.

70 Also mounted on the clock shaft and preferably integral with the gear 69 is a pinion 75 adapted to mesh with a gear 76 fixed on an axle journaled in the front frame member 30 and carrying on its other end in front of the front frame a pinion 78 which meshes with and drives a gear 79 carried with the sleeve 66.

75 By suitably proportioning the train of gears just described in a manner well understood the hands 18, 19 are propelled over the face 17 of the clock to indicate standard periods of time, to wit, hours and minutes.

80 By suitably proportioning the train of gears just described in a manner well understood the hands 18, 19 are propelled over the face 17 of the clock to indicate standard periods of time, to wit, hours and minutes.

85 Thus the elapsed time indicators, 15, 16, are driven from and the clock hands 18, 19 move in unison with gear 45 carried with the outer clutch member 42 which is rotatable on the hub of the inner member 26. The rotation of gear 45 is thus controlled by the escapement 27 and its rotation is permitted in only one direction to wit, clockwise, by the ball clutch. The rewinding of the spring and hence the storing of the potential in the power means, which is the spring, is effected by turning the center shaft in a counter clockwise direction during which operation the escapement, and the standard time or clock gearing are momentarily unclutched from the center shaft. The center shaft 24 is turned in counter clockwise direction by 90 electro-magnetic devices, now to be described, which, because of their construction, effect the rewinding by a step by step movement. Each step of rewinding is of extremely short duration, so that the momentum of the escapement is enabled to continue the operation of the standard time mechanism, without retardation or variation due to the interaction of the escapement gearing and the standard time clock gearing.

95 Reference will now be had to Figures 7 through 10 and Figure 13 for an understanding of the construction of electro-magnetic devices and their operation which are rendered operative to restore the potential in the power means, to wit, the main spring, and return the elapsed time indicating means to initial position when the device in which the indicator is installed moves or operates.

100 In axial alignment with the center shaft 24, is what may be termed for convenience, an armature shaft 81 (Figure 6) which is operatively connected with the center shaft by a ball clutch whereof the inner member 82 is

removably secured to the forward end of the armature shaft 81 and the outer member 83 is carried for rotation with the end of the center shaft 24 by a joint capable of 5 relative movement to compensate for inequalities in alignment of the two shafts. The end of shaft 24 is rectangular as at 29 and is disposed within a slot 86 formed in a head 87 carried by the clutch member 83. 10 A helical spring 25 surrounds the head 87 between the abutment 85 and the clutch member 83 to contribute to the alignment of the parts. The clutch is illustrated in detail in Figure 11 from which it will be understood that 15 rotation of the armature shaft in a counter clockwise direction will turn with it the center shaft 24 and thereby wind the main spring 20 through the pinion and gear connection 37 and 38 while rotation of the armature shaft in the opposite direction does not affect the center shaft 24.

The balls 88 serve to lock the clutch members 82 and 83, Figure 11, for rotation together in clockwise direction as viewed in 25 that figure but in a counter clockwise direction, with respect to the face of the clock 17 as will be understood, when shaft 81 is rotated in clockwise direction as viewed in Figure 11 for a purpose which will be more 30 apparent hereafter, as it is desirable that shaft 24 be free for rotation in the operation of the clock mechanism. The balls 88 are therefore held in a neutral position by forks 89 integral with the rocking lever 84 fulcrumed on the hub 44 of the clutch member 82. A spring 102 carried on the frame member 105 retards said lever 84 when returning to its neutral position, its stopping point being assured or effected by a spring 107. 35

40 The rear end of armature shaft 81 carries what may be described as a two pole armature 90 rotatable within the diametrically opposite pole pieces 91 and forming with the armature what is in effect an electric motor.

Referring particularly to Figure 13, current from a source of electrical energy 22, say a storage battery, flows by the conductor 101, to the coils 103, of the field magnet 92 50 for the motor pole pieces 91. From the field magnet the current returns to the battery 22 through circuit closing devices operable automatically dependent upon the movement or operation of the device on which the 55 indicator is mounted.

Assuming, for the sake of convenience in description, that the indicator or parking clock is mounted upon a motor vehicle, a vibrator or trembler 110 in the form of one 60 arm of a bell crank lever 102 is pivotally mounted as at 111 upon a transverse frame member 105 and is adapted to be brought into contact with a pair of spaced pole pieces 112 by the swaying of the vehicle. These pole pieces 112 are electromagnets electrically

connected, by the conductor 113, with the positive terminal of the battery 22 and through a conductor 114 with a pair of normally closed contacts 115, 116, conductor 117, electromagnets 112, trembler 110, and conductor 118 to the ground G. Thus when the trembler 110 contacts with the pole piece, the circuit is completed which energizes electromagnets 112 and they retain the trembler in circuit closing position to energize the field 75 of the motor so long as contacts 115 and 116 are closed.

Contact 115 is resiliently carried upon an insulating block 119 secured to one arm of a lever 104 pivoted as at 124 upon frame member 105 said lever 104 being normally retained by the spring 120 in such position that the contacts 115, 116 are normally closed. As a practical expedient conductor 114 is 80 connected with a resilient leaf 121 which is always in wiping contact with a similar resilient leaf 122 carried on the pivoted block 119 in electrical connection with the resilient arm 123 carrying the contact 115 so that regardless of the position of the block 119 as it 85 pivots about the fulcrum 124 an electrical connection will always be assured through the contacts 121, 122.

The closing of the contacts 110 and 112 also completes the circuit including the battery 95 and the motor and hence energizes the motor field since coil 103 of the field magnet is in circuit with electrical conductors 106, and contacts 108, 109 which are normally closed. Contact 109 is carried upon a resilient frame 100 130 mounted upon a metallic rocking member 131 pivoted at 137 on insulator 134 and operatively connected by bar 132 through a conductor 133 with the contact 121 and from thence to the ground as hereinbefore described.

Thus, so soon as the trembler 110 makes an electrical contact with the pole pieces 112, the field magnet 92 is energized together with the armature 90, the winding of which is energized by a shunt connection between conductors 101, 106. The armature 90 is thereupon caused to rotate immediately in the direction indicated by the arrow X about the axis of the armature shaft 81 and thereby 115 turning the armature shaft in a counter clockwise direction to wind the spring as previously described. That is, during the rotation of the armature shaft 81 in counter clockwise direction, the center shaft 24 is 120 clutched to the armature shaft 81 and is rotated therewith to wind the mainspring 20 through the gearing 37 and 38. This rotation of the shaft 81 takes place through only a relatively small angle and is extremely 125 rapid in order to permit the momentum of the escapement to continue the operation of the standard time mechanism without interruption, the escapement and standard time 130 clock mechanism being disconnected by the

ball clutch from the center shaft for that purpose as has been explained. The armature 90 rotates in a counter clockwise direction until an insulated pin 135 carried there-
 5 by contacts with one arm 136 of the rocking member 131 rotating it about its pivot 137 to carry the contact 109 away from the contact 108 and break the circuit including the motor field 103 and deenergize the motor pole
 10 pieces. A spring 139 immediately returns the armature to initial position as shown in Figure 9 bringing the pin 135 in contact with the other arm 140 of the rocking member 131 to rock that member about the pivot 137
 15 and carry the contact 109 again in contact with contact 108 to close the circuit and permit the reenergization of the motor which effects another rotation of the armature shaft in counter clockwise direction, as before.
 20 During the movement of the armature under the influence of the spring 139, i. e. the returning movement, the armature shaft 81 is disconnected or unclutched from the center shaft 24 by the ball coupling so that the
 25 spring remains wound by the partial revolution of the armature shaft 81 just described. During the return movement of the armature shaft 81 the clutch 26 engages with the escapement, so there is no backlash and this
 30 serves as retarding means. So soon as the motor is energized a succeeding time the armature is again turned to the position shown in Figure 10 which effects a further rotation of the center shaft 24 and a further tensioning of the main spring.
 35

It must be borne in mind that this movement which results in the winding of the main spring 20 also returns the elapsed time indicators 15, 16 to the initial or zero position by a step by step movement coinciding with the step by step winding of the main spring 20 so that when the mainspring 20 is fully wound up the elapsed time hands 15, 16 are at zero or initial position.

40 45 The alternate energization and deenergization of the motor continues until the step by step rotation of the main spring arbor 28 completely winds the main spring. As viewed from Fig. 13, main spring arbor 28 rotates in a clockwise direction when rewinding which brings a cam 142 into contact with a shoulder 143 carried upon the arm 144 of the bell crank forming the trembler 110 and serves to depress the arm 144 so that
 50 55 the contact 110 is retained in circuit closing position to keep the arm 144 rigid and motionless until such time as the spring requires further winding.

A portion of the cam 142 or a second cam 141 also carried on the end of the power spring arbor 28 also depresses, at about the same time, an arm 145 of the pivoted lever 104 heretofore referred to as carrying the pivoted block 119 rotating the block about
 60 65 its pivot 124 against the action of the spring

120 to open the contacts 115, 116 and thereby interrupt the several circuits including battery 22 so that subsequent or continued vibration or swaying of the vehicle after the main spring has been fully wound, will not deplete the storage battery 22 and waste electric current.

70 Of course during the further or continued operation of the conveyance the standard time clock continues to function thereby necessitating the unwinding of the main spring 20 to some extent. This unwinding of the main spring however, results in the rotation of the main spring arbor 28 to bring the cams 141, 142 out of contact with the arms 144, 145 thereby permitting the contacts 115, 116 to close quickly under the influence of the spring 120 and the trembler 110 to operate to energize the motor and rewind the
 75 80 85 spring as described.

90 The parts are so proportioned that when the main spring 20 is unwound to the point where winding it again will just return pointers 15, 16 to zero position, the cam 142 on the main spring arbor 28 comes around in a contra-clockwise rotation as viewed in Fig. 13 and contacts with the other face of the projection 143 on the bellcrank 102 to rotate the bell crank to again close contacts 110, 112 to reenergize the motor and wind up spring 20. It will be noted that arm 104 is cut away or recessed to such an extent that cam 141 does not contact with arm 104 and therefore the spring 120 is effective to hold the contacts 115, 116 closed. This occurs after six hours of operation of the elapsed time indicating mechanism. Six hours operation has been adapted arbitrarily as it is unlikely that municipal parking ordinances will attempt to regulate parking in situations where it is unobjectionable for that length of time.

95 100 105 110 115 120 125 130 From an inspection of Figure 3 it will be observed that what may be termed broadly, clock mechanism is carried between a pair of frame members 30, 31 spaced by posts 146 and that the electro magnetic devices are carried by the frame member 105 from posts 147, the frame member 105 being suitably spaced from but carried rigidly on the clock mechanism frame by posts 148. Thus a compact structure is provided which is interconnected as a unit and carries, by the posts 149, the face 15 upon which the dials 14, 17 are depicted. The entire structure is thus conveniently supported within a casing or housing 151 which may be carried say on the vehicle for convenient observation and reference. Obviously the supporting frame 30, 31, 105 moves with the device upon which it is mounted and for the purposes of description the frame may be looked upon as the device, the movement of which affects operation of the mechanism although it will be obvious that by the term de-

vice any instrumentality is intended to be covered.

It is thought that the operation of the indicator is apparent from the foregoing description. It will be observed that the main spring 20 is wound by a periodic turn of the center shaft 24 in one direction of rotation by what is in effect a motor and that this periodic turn of the center shaft 24 returns the 10 elapsed time indicators 15, 16 to initial position. While the vehicle is in operation this vibration or swaying serves to close the electrical circuit which energizes the motor and the rotation thereof is transmitted to the center shaft by a ball clutch to rotate the same. Movement of the motor armature through the predetermined angle serves to interrupt the current energizing the pole pieces of the motor and permits a spring to return the armature to initial position when the circuit is again established and the armature again turned to cause a further turning of the center shaft 24.

Various modifications may be made in the 25 disposition and configuration of the circuit closing devices and their manner of actuation without departing from the spirit and scope of the invention as set forth in the appended claims.

30 What I claim is:

1. In an elapsed time indicator, the combination, with a device upon which the indicator is mounted, of potential power means, elapsed time indicating means, operative connections between said power means and the indicating means, means to restore the potential in the power means, means to return the elapsed time indicating means, means to initiate the operation of said last two means 35 dependent upon the movement of the device upon which the indicator is mounted and means to retain said last named means in operative position during movement of the device.

40 2. In an elapsed time indicator, the combination, with a device upon which the indicator is mounted, of potential power means, elapsed time indicating means, operative connections between said potential and the indicating means, returning means to restore the potential in the power means and to return the elapsed time indicating means, means to initiate the operation of said returning means dependent upon the movement of the device 45 upon which the indicator is mounted and means to retain said last named means in operative position during movement of the device.

50 3. In an elapsed time indicator, the combination, with a device upon which the indicator is mounted, of potential power means, elapsed time indicating means, operative connections between said potential and the indicating means, means to restore the potential 55 in the power means by a step by step move-

ment, means to return the elapsed time indicating means, means to initiate the operation of said last two means dependent upon the movement of the device upon which the indicator is mounted and means to retain said last named means in operative position during 70 movement of the device.

4. In an elapsed time indicator, the combination, with a device upon which the indicator is mounted, of potential power means, elapsed time indicating means, operative connections between said potential and the indicating means, means to restore the potential in the power means, means to return the elapsed time indicating means by a step by 75 step movement, means to initiate the operation of said last two means dependent upon the movement of the device upon which the indicator is mounted and means to retain said last named means in operative position 80 during movement of the device.

5. In an elapsed time indicator, the combination, with a device upon which the indicator is mounted, of potential power means, elapsed time indicating means, operative connections between said potential and the indicating means, means to restore the potential in the power means and to return the elapsed time indicating means by a step by 85 step movement, means to initiate the operation of said last named means dependent upon the movement of the device upon which the indicator is mounted and means to retain said last named means in operative position 90 during movement of the device.

6. In an elapsed time indicator, the combination, with a device upon which the indicator is mounted, of potential power means, elapsed time indicating means, escapement mechanism, operative connections between said potential power means and the indicating means and between the potential power means and the escapement mechanism, returning means to restore the potential in the power means and to return the elapsed time indicating means, means to render inoperative the first named connections while said returning means is functioning, means to initiate the operation of said returning means dependent upon the movement of the device upon which the indicator is mounted and means to retain said last named means in operative position during movement of the device. 100

7. In an elapsed time indicator, the combination, with a device upon which the indicator is mounted, of potential power means, elapsed time indicating means, escapement mechanism, operative connections between said potential power means and between the potential power means and the indicating means and the escapement mechanism, returning means to restore the potential in the power means and means to return the elapsed time indicating means, means to render in- 110 115 120 125 130

operative said operative connections when the returning means is functioning, means to initiate the operation of said returning means dependent upon the movement of the device 5 upon which the indicator is mounted and means to retain said last named means in operative position during movement of the device.

8. In an elapsed time indicator, the combination, with a device upon which the indicator is mounted, of potential power means, elapsed time indicating means, standard time indicators, escapement mechanism, operative connections between said potential power 15 means and the indicating means, standard time indicators and escapement mechanism, respectively, returning means to restore the potential in the power means and to return the elapsed time indicating means, means to render inoperative the connections between the potential power means and the standard time indicators or escapement mechanism when the returning means is functioning, 20 means to initiate the operation of said returning means dependent upon the movement of the device upon which the indicator is mounted and means to retain said last named means in operative position during movement of the device.

9. In an elapsed time indicator, the combination, with a device upon which the indicator is mounted, of potential power means, elapsed time indicating means, escapement mechanism, operative connections between 35 said potential power means and the indicating means, operative connections between the potential power means and the escapement mechanism, returning means to restore the potential in the power means and to return the elapsed time indicating means, said last named connections being constructed to become automatically inoperative when the returning means are functioning, means to initiate the operation of said returning means 40 dependent upon the movement of the device upon which the indicator is mounted and means to retain said last named means in operative position during movement of the device.

10. In an elapsed time indicator, the combination, with a device upon which the indicator is mounted, of potential power means, elapsed time indicating means, standard time indicating means, escapement mechanism, operative connections between said potential power means and the indicating means, operative connections between the potential power means and the standard time indicating means and escapement mechanism, returning means to restore the potential in the power means and to return the elapsed time indicating means, said last named connections being constructed to become automatically 55 inoperative when the returning means is functioning, means to initiate the operation

of said returning means dependent upon the movement of the device upon which the indicator is mounted and means to retain said last named means in operative position during movement of the device. 70

11. In an elapsed time indicator, the combination, with a device upon which the indicator is mounted, of potential power means, elapsed time indicating means, standard time indicating means, escapement mechanism, operative connections between said potential power means and the elapsed time indicating means, operative connections between the power means and the standard time indicating means, operative connections between the power means and the escapement mechanism, operative connections between the escapement mechanism and the standard time indicating means, returning means to restore the potential in the power means and to return the elapsed time indicating means to initial position, the last two named operative connections being constructed to become inoperative upon operation of the returning means, retarding means to prevent retrograde movement of the returning means, means to initiate the operation of said returning means dependent upon the movement of the device upon which the indicator is mounted and means to retain said last named means in operative position during movement of the device. 85 90

12. An elapsed time indicator comprising, in combination, a composite shaft, clutch means permitting relative movement in one direction between shaft sections, electro-magnetic means to rotate one shaft section in one direction, tension means to rotate the shaft section in the opposite direction, mechanical means to rotate another shaft section in the opposite direction, elapsed time indicating means rotated from the last named shaft section and means to set the indicator in motion upon occurrence of an event. 100 105 110

13. An elapsed time indicator comprising, in combination, a composite shaft, clutch means permitting relative movement in one direction between shaft sections, electro-magnetic means to rotate one shaft section in one direction, tension means to rotate said shaft section in the opposite direction, mechanical means to rotate another shaft section in one direction, indicating means rotated from the last named shaft section, standard time indicating means and escapement mechanism, driving connections between the standard time indicating means and escapement mechanism and the last named shaft section, said driving connection being constructed to become inoperative upon rotation of the second named shaft section in the opposite direction. 115 120 125

14. An elapsed time indicator comprising, in combination, a composite shaft, clutch means permitting relative movement in one 130

- direction between shaft sections, electro-magnetic means to rotate the composite shaft in one direction, mechanical means to rotate a shaft section in the opposite direction, indicating means rotated from said shaft section, standard time indicators, escapement mechanism, driving connections for the standard time indicating and escapement mechanism including clutch means between said mechanism and the said shaft section operative upon rotation of the shaft section by the mechanical means.
15. An elapsed time indicator comprising, in combination, a composite shaft, clutch means permitting relative movement in one direction between shaft sections, electro-magnetic means to rotate a shaft section in the same direction, tension means to rotate said shaft section in the opposite direction, means to insure the inoperativeness of said clutch means upon rotation of the shaft section by the tension means, mechanical means to rotate another shaft section in the opposite direction, elapsed time indicating means rotated from said second named shaft section, standard time indicators, escapement mechanism, driving connections for the standard time indicators and escapement mechanism including clutch means between said mechanism and the said second named shaft section operative upon rotation of the second named shaft section by the mechanical means.
16. An elapsed time indicator comprising, in combination, a sectional shaft, clutch means permitting relative movement on one direction between shaft sections, tension means to rotate a shaft section in one direction, electro-magnetic means upon a second shaft section to rotate the sectional shaft in the opposite direction to restore the potential in the tension means, elapsed time indicating means rotated from said first named shaft section, standard time indicators, escapement mechanism, interacting driving connections for the standard time indicators and escapement mechanism including clutch means between said mechanism and said last named shaft section operative upon rotation of the shaft section by the tension means.
17. An elapsed time indicator comprising, in combination, a sectional shaft, clutch means permitting relative movement in one direction between shaft sections, a main spring to rotate a shaft section in one direction, electro-magnetic means to rotate the sectional shaft in the opposite direction, to restore the potential in the main spring, elapsed time indicating means rotated from said first named section, standard time indicating means, escapement mechanism, interacting driving connections for the standard time indicating means and escapement mechanism including clutch means between said mechanism and the said shaft section operative upon rotation of the shaft section by the main
- spring, and means to energize the electro-magnetic means dependent upon movement of the elapsed time indicator as a whole.
18. An elapsed time indicator comprising, the combination with a device upon which the indicator is mounted and a source of electrical energy, of a sectional shaft, clutch means permitting relative movement in one direction between shaft sections, a main spring, to rotate a shaft section in one direction, electro-magnetic means to rotate the sectional shaft in the opposite direction, to restore the potential in the main spring, elapsed time indicating means rotated from the first named shaft section, standard time indicating means, escapement mechanism, interacting driving connections for the standard time indicating means and escapement mechanism including clutch means between said mechanism and the first named shaft section operative upon rotation of the shaft section by the main spring, an electrical circuit including the source of electrical energy and the electro-magnetic means, and a vibrator responsive to movements of the device upon which the indicator is mounted, adapted to close the circuit when the said device has movement.
19. An elapsed time indicator comprising, the combination with a device upon which the indicator is mounted and a source of electrical energy, of a sectional shaft, clutch means permitting relative movement in one direction between shaft sections, a main spring to rotate a shaft section in one direction, electro-magnetic means to rotate the sectional shaft in the opposite direction, elapsed time indicating means propelled from said first named shaft sections, standard time indicating means, escapement mechanism, interacting driving connections for the standard time indicating means and escapement mechanism including clutch means between said mechanism and the said first named shaft section operative upon rotation of the shaft section by the main spring, an electrical circuit including the source of electrical energy and the electro-magnetic means, a trembler responsive to movement of the device to close the circuit and automatic means to open the circuit when the potential is restored in the main spring.
20. An elapsed time indicator comprising, the combination with a device upon which the indicator is mounted and a source of electrical energy, of a sectional shaft, clutch means permitting relative movement in one direction between shaft sections, a main spring to rotate a shaft section in one direction, electro-magnetic means to rotate the sectional shaft in the opposite direction, elapsed time indicating means propelled from said first named shaft section, standard time indicating means, escapement mechanism, interacting driving connections for the standard time indicating means and escapement mechanism including clutch means between said mechanism and the said shaft section operative upon rotation of the shaft section by the main

standard time indicating means and escapement mechanism including clutch means between said mechanism and the said first named shaft section operative upon rotation 5 of the shaft section by the main spring, an electrical circuit including the source of electrical energy and the electro-magnetic means, a trembler responsive to movement of the device to close the circuit, automatic means to 10 open the circuit when the potential is restored in the main spring, and means to retain the trembler in circuit closing position.

21. An elapsed time indicator comprising, the combination with a device upon which 15 the indicator is mounted and a source of electrical energy, of a sectional shaft, clutch means permitting relative movement in one direction between shaft sections, a main spring to rotate a shaft section in one direction, electro-magnetic means to rotate the sectional shaft in the opposite direction, elapsed time indicating means propelled from said first named shaft section, standard 20 time indicating means, escapement mechanism, interacting driving connections for the standard time indicating means and escapement mechanism including clutch means between said mechanism and the said first named shaft section operative upon rotation 25 of the shaft section by the main spring, an electrical circuit including the source of electrical energy and the electro-magnetic means, a trembler responsive to movement of the device to close the circuit, automatic 30 means to open the circuit when the potential is restored in the main spring, and retain the trembler in circuit closing position.

22. An elapsed time indicator comprising, the combination with a device upon which 40 the indicator is mounted and a source of electrical energy, of a sectional shaft, clutch means permitting relative movement in one direction between shaft sections, a main spring to rotate a shaft section in one direction, electro-magnetic means to rotate the sectional shaft in the opposite direction, elapsed time indicating means propelled from said first named shaft section, standard 45 time indicating means, escapement mechanism, interacting driving connections for the standard time indicating means and escapement mechanism including clutch means between said mechanism and the said first named shaft section operative upon rotation 50 of the shaft section by the main spring, an electrical circuit including the source of electrical energy and the electro-magnetic means, a trembler responsive to movement of the device to close the circuit, automatic 55 means to open the circuit when the potential is restored in the main spring, and retain the trembler in circuit closing position, and means to close the circuit after a predetermined 60 exhaustion of potential in the main spring, and means to deenergize the electro-magnetic means upon a predetermined movement thereof.

23. An elapsed time indicator comprising, the combination with a device upon which the indicator is mounted and a source of electrical energy, of a sectional shaft, clutch means permitting relative movement in one 70 direction between shaft sections, a main spring to rotate a shaft section in one direction, electro-magnetic means to rotate the sectional shaft in the opposite direction, elapsed time indicating means propelled 75 from said first named shaft section, standard time indicating means, escapement mechanism, interacting driving connections for the standard time indicating means and escapement mechanism including clutch means between said mechanism and the said first named shaft section operative upon rotation 80 of the shaft section by the main spring, an electrical circuit including the source of electrical energy and the electro-magnetic means, a trembler responsive to movement of the device to close the circuit, automatic means to open the circuit when the potential is restored in the main spring, and retain the trembler in circuit closing position, means to close the circuit after a predetermined exhaustion of potential in the main spring, and means to deenergize the electro-magnetic means upon a predetermined movement thereof.

24. An elapsed time indicator comprising, the combination with a device upon which the indicator is mounted and a source of electrical energy, of a sectional shaft, clutch means permitting relative movement in one 100 direction between shaft sections, a main spring to rotate a shaft section in one direction, electro-magnetic means to rotate the sectional shaft in the opposite direction, elapsed time indicating means propelled from said first named shaft section, standard time indicating means, escapement mechanism, interacting driving connections for the standard time indicating means and escapement mechanism including clutch means between 105 said mechanism and the said first named shaft section operative upon rotation of the shaft section by the main spring, an electrical circuit including the source of electrical energy and the electro-magnetic means, a trembler responsive to movement of the device to close the circuit and automatic means to open the circuit when the potential is restored in the main spring, and retain the trembler in circuit closing position, means to close the circuit after a predetermined exhaustion of potential in the main spring, means to deenergize the electro-magnetic means upon a predetermined movement thereof, a spring to return the electro-magnetic means to initial 110 position and means to reenergize the electro-magnetic means upon return to initial position.

25. An elapsed time indicator comprising, the combination, with a source of electrical 115

- energy, of a composite shaft, clutch means permitting relative movement in one direction of rotation between shaft sections, electro-magnetic means to rotate the composite shaft in one direction, mechanical means to rotate a shaft section in the opposite direction, elapsed time indicating means directly propelled by said last named shaft section, and electrically responsive means to control the energization of the electro-magnetic means dependent upon movement of the device upon which the indicator is carried. 26. An indicator comprising, the combination, with a source of electrical energy, of a composite shaft, clutch means permitting relative movement in one direction of rotation between shaft sections, electro-magnetic means to rotate the composite shaft in one direction, mechanical means to rotate a shaft section in the opposite direction, elapsed time indicating means directly propelled by said last named shaft section, and electrically responsive means to energize the electro-magnetic means upon movement of the device upon which the indicator is carried. 27. An indicator comprising, the combination, with a source of electrical energy, of a composite shaft, clutch means permitting relative movement in one direction of rotation between shaft sections, electro-magnetic means to rotate the composite shaft in one direction, mechanical means to rotate shaft section in the opposite direction, elapsed time indicating means directly propelled by said last named shaft section electrically responsive means to permit the energization of the electro-magnetic means dependent upon movement of the device upon which the indicator is carried, and mechanical means to retain said electrically responsive means in operation. 28. An indicator comprising, the combination, with a source of electrical energy, of a composite shaft, clutch means permitting relative movement in one direction of rotation between shaft sections, electro-magnetic means to rotate the composite shaft in one direction, mechanical potential power means to rotate shaft section in the opposite direction, elapsed time indicating means directly propelled by said last named shaft section, electrically responsive means to effect the energization of the electro-magnetic means dependent upon movement of the device upon which the indicator is carried, and mechanical means dependent upon the potential in the power means to control the electrically responsive means. 29. An indicator comprising, the combination, with a source of electrical energy, of a composite shaft, clutch means permitting relative movement in one direction of rotation between shaft sections, electro-magnetic means to rotate the composite shaft in one direction, mechanical potential power means to rotate shaft section in the opposite direction, elapsed time indicating means directly propelled by said last named shaft section, electrically responsive means to effect the energization of the electro-magnetic means dependent upon movement of the device upon which the indicator is carried, and mechanical means dependent upon the potential in the power means to retain the electrically responsive means in operative position, other mechanical means dependent upon the potential in the power means to deenergize the electro-magnetic means, and means dependent upon the potential in the power means to reenergize the electro-magnetic means. 30. An indicator comprising, the combination, with a source of electrical energy, of a composite shaft, clutch means permitting relative movement in one direction of rotation between shaft sections, electro-magnetic means to rotate the composite shaft in one direction, mechanical potential power means to rotate shaft section in the opposite direction, elapsed time indicating means directly propelled by the latter shaft section, electrically responsive means to effect the energization of the electro-magnetic means dependent upon movement of the device upon which the indicator is carried, mechanical means dependent upon the potential in the power means to retain the electrically responsive means in operative position, other mechanical means dependent upon the potential in the power means to deenergize the electro-magnetic means, and means dependent upon the potential in the power means to reenergize the electro-magnetic means. 31. An indicator comprising, the combination, with a source of electrical energy, of a composite shaft, clutch means permitting relative movement in one direction of rotation between shaft sections, electro-magnetic means to rotate the composite shaft in one direction, mechanical potential power means to rotate a shaft section in the opposite direction, elapsed time indicating means directly propelled by said last named shaft section, electrically responsive means to effect the energization of the electro-magnetic means dependent upon movement of the device upon which the indicator is carried, mechanical means dependent upon the potential in the power means to retain the electrically responsive means in operative position, other mechanical means dependent upon the potential in the power means to deenergize the electro-magnetic means and to reenergize said means when the device has no movement. 32. An indicator comprising, in combination, with a source of electrical energy, of a sectional shaft, clutch means permitting relative movement in one direction of rotation between shaft sections, electro-magnetic means to rotate the sectional shaft in one direction, mechanical potential power means to rotate a shaft section in the opposite direction, elapsed time indicating means directly

propelled by said last named shaft section, electrically responsive means to effect the energization of the electro-magnetic means dependent upon movement of the device upon which the indicator is carried, means to de-energize the electro-magnetic means upon a predetermined movement thereof, returning means to return the electro-magnetic means to initial position and means to reenergize the electro-magnetic means upon return to initial position.

33. An indicator comprising, the combination, with a source of electrical energy, of a sectional shaft, clutch means permitting relative movement in one direction of rotation between shaft sections, a motor to rotate the sectional shaft in one direction, a main spring to rotate a shaft section in the opposite direction, elapsed time indicators directly 20 propelled by said last named shaft section, electrically responsive means to effect the energization of the motor dependent upon movement of the device upon which the indicator is carried, a cam movable by the main 25 spring to retain the electrically responsive means in operative position and another cam movable by the main spring to effect the de-energization of the motor.

34. An indicator comprising, the combination, with a source of electrical energy, of a sectional shaft, clutch means permitting relative movement in one direction of rotation between shaft sections, a motor to rotate the sectional shaft in one direction, a main 35 spring to rotate a shaft section in the opposite direction, elapsed time indicators directly propelled by said last named shaft section, electrical responsive means to effect the energization of the motor dependent upon movement of the device upon which the indicator is carried, a locking cam movable by the main 40 spring to retain the electrically responsive means in operative position and to de-energize the motor.

45. 35. An indicator comprising, the combination, with a source of electrical energy, of a sectional shaft, clutch means permitting relative movement in one direction of rotation between shaft sections, a motor to rotate the sectional shaft in one direction, an electric 50 circuit including the motor and source of electrical energy, a main spring to rotate a shaft section in the opposite direction, elapsed time indicators directly propelled by said shaft section, electrically responsive means to effect the energization of the motor dependent upon movement of the device upon which the indicator is carried, a locking cam movable by the main 55 spring to re-

tain the electrically responsive means in operative position, another cam movable by the main spring to effect the deenergization of the motor, contacts in the electric circuit, means operative by the armature to open the 60 contacts upon movement thereof in one di-

rection and to close the contacts upon movement thereof in the opposite direction.

36. An elapsed time indicator comprising the combination with a device upon which the indicator is mounted and a source of electrical energy, of a frame, a center shaft journalled in the frame, an arbor journalled in the frame, a main spring carried by the arbor to rotate the same, gearing between the arbor and the center shaft, an elapsed time 70 indicator hand carried on the end of the shaft, a dial over which the hand travels, a ball clutch carried by the center shaft, a gear carried with the ball clutch, escapement mechanism driven by the gear, a standard time dial, standard time indicating hands 75 propelled over the time dial by the gear, an armature shaft, a ball clutch between the armature shaft and the center shaft, a motor comprising an oscillatory armature carried 80 by the armature shaft, and an electromagnet to energize the motor, a rocking lever, a stationary contact, a movable contact carried with the lever in circuit with the motor and the source of electrical energy, a pin carried 85 by the armature to rock the lever to open and close the circuit, a trembler responsive to movement of the device upon which the indicator is carried and an electromagnet in electrical connection with the source of electrical 90 energy with which the trembler is adapted to contact to close the circuit and energize the electromagnet, a pair of normally closed contacts in the circuit, a cam surface carried by the arbor and movable from normal position 95 to retain the trembler in contact with the electromagnet and to open the last named contacts when the mainspring is fully wound and movable to normal position to close the contacts when the mainspring is unwound 100 to a predetermined degree when the device upon which the indicator is mounted has no movement.

37. A time indicator comprising a shaft, potential power means to drive the shaft in one direction, standard time indicating means, clutch mechanism connecting the standard time indicating means with the shaft to actuate the former and releasing the connection when the shaft is rotated in the opposite direction, vibrating means mounted to vibrate upon jarring of the indicator, rewinding means for the potential power means actuated by the vibration of the vibrating means, and clutch means connecting the rewinding means with the shaft to rotate the latter in a direction opposite to the direction of rotation caused by the potential power means.

38. A time indicator comprising a shaft, potential power means to drive the shaft in one direction, standard time indicating means, clutch mechanism connecting the standard time indicating means with the shaft to actuate the former and releasing the 125

- connection when the shaft is rotated in the opposite direction, electro-magnet means, a clutch connecting the electromagnetic means with the shaft to rotate the latter in a direction opposite to the direction of rotation caused by the potential power means, and switching means controlling the actuation of the electro-magnet means upon vibration thereof.
- 10 39. An elapsed time indicator comprising a composite shaft having two shaft sections, potential power means connected to a first shaft section to rotate the section in one direction, electro-magnetic means connected to the second shaft section to rotate the section, clutch means connecting the second shaft section to the first shaft section for rotation of the latter in a direction opposite to the direction of rotation caused by the potential power means, elapsed time indicating means connected with the first shaft section, and trembler switch means to actuate the electro-magnet means upon vibration thereof.
